IRONING-BOARD ATTACHMENT

Application filed June 12, 1928. Serial No. 284,703.

Our invention relates to ironing boards and it has for a purpose the provision of an attachment therefor by which those parts of the garment which have been pressed, but are not actually supported on the ironing board 5 so that they depend from the board as a result of shifting the garment to press other portions thereof, are effectively supported to preserve their pressed condition and to prevent 10 contacting with the floor and consequent soiling.

It is also a purpose of our invention to provide an ironing board attachment which embodies a tray supported by the ironing board 15 and adjustable to assume any required level to properly support the parts of a garment depending from the board to prevent wrinkling thereof, the tray being also movable to either side of the board to facilitate access 20 thereto and to support the depending parts of a garment at either side of the board.

A further purpose of our invention is the provision of an ironing board attachment which includes a bracket vertically adjustable 25 on the tray and designed to support a coat hanger, which latter, in applied position to a garment, is held in elevated position to sustain the garment in elevated position at the end of the board and to thereby prevent 30 wrinkling of the garment.

We will describe only one form of garment-supporting attachment for ironing boards embodying our invention and will then point out the novel features in claims. 35

In the accompanying drawings:

Figure 1 is a view showing in perspective one form of garment-supporting attachment embodying our invention in applied position to an ironing board;

Fig. 2 is a vertical longitudinal sectional view of the attachment and board shown in Fig. 1;

Fig. 3 is a plan perspective view of the attachment and ironing board shown in the preceding figures with a garment in applied position thereon;

Fig. 4 is a vertical sectional view taken on the line 4-4 of Fig. 3; and

Fig. 5 is an enlarged detail view of the 50 post and bracket embodied in the attachment

shown in the preceding views, the bracket being shown in section.

In carrying out our invention we employ an ironing board B of conventional form and which, as shown in Fig. 1, is supported in horizontal position against a wall by a diagonal supporting leg L. Screwed to the under side of the board B is a disk 15 having a central collar 16 interiorly threaded to receive the upper end of a depending post 17. As shown in Fig. 5, this post is screw-threaded throughout its length with its lower end provided with a nut 18 to prevent downward displacement of a bracket 19 from the post.

The bracket 19 is of U-form in cross-section with its parallel portions provided with registering openings of a size to loosely receive the post 17 so that when the bracket is in a horizontal position it is freely movable vertically on the post. However, when the bracket is moved to an angular position, indicated in dotted lines, the walls of the bracket openings engage the threads of the post and thus lock the bracket against vertical movement on the post.

A tray T is secured to the bracket 19, and the weight of the tray is sufficient to move the bracket to the dotted-line position, thereby maintaining a vertical adjustment of the bracket, and as a consequence the vertical adjustment of the tray. The weight of the tray can be removed from the bracket by lifting the former to a truly horizontal position, thus causing the bracket to occupy a corresponding position and thereby releasing the bracket to permit its upward adjustment on the post. In this manner the tray can be readily adjusted vertically to any desired level beneath the ironing board within the limits of the post, and when released the bracket will automatically function to maintain such adjustment. The bracket 19 also provides a connection between the post and tray that permits the tray to be swung from its position beneath the ironing board to a position at either side of the ironing board, and all without disturbing its level of adjustment.

The tray, in the present instance, comprises a wooden frame 20 spanned by a wire screen

21. The tray is preferably wider than the ironing board B and is so mounted thereon that one end projects beyond the free end of the board as illustrated in Fig. 2.

5 The projecting end of the tray is provided with a bracket K having a linear portion 22 adjustable vertically in a sleeve 23 secured to the frame 20, and provided with a set-screw 24 by which the bracket can be secured in any 10 vertically adjusted position. The upper end of the bracket K is formed with a hook 25 upon which a coat hanger 26 may be supported, the latter in turn adapted to be inserted in a garment for sustaining one end of 15 the garment in elevated position in respect to the ironing board. The bracket K includes a substantially U-shaped portion 27, which allows the coat hanger to be sustained from the hook 25 and to thus support a garment 20 out of contact with the bracket.

In practice, the tray T, being disposed below the ironing board B, functions to sustain the pressed parts of a garment against hanging at full length from the board, as illustrated in Figs. 3 and 4, whereby the garment 25 is supported against wrinkling and the pressed condition of its parts preserved. In this manner the several parts of a garment 30 can be pressed and maintained so throughout the pressing of the entire garment and without fear of the garment contacting with the floor and soiling the same. By placing a hanger 26 upon the bracket K, the neck and shoulder portion of a garment can be sustained in elevated position at the outer end 35 of the board, as illustrated in Fig. 3, thus facilitating pressing of the garment and preventing wrinkling of the shoulder and sleeve portions of the garment.

40 The tray T can be adjusted vertically, as previously described, and for the purpose of supporting the depending parts of a garment at any desired level within the limits of adjustment of the bracket 19 to prevent wrinkling of such parts, and to sustain them out of contact with the floor. The tray T can also be swung to either side of the ironing board to support depending parts of a garment at either side of the board. The bracket K is 45 also adjustable vertically to sustain a coat hanger to successfully support the shoulder portion of a garment in elevated position at the outer end of the board.

55 Although we have herein shown and described one form of garment-supporting attachment for ironing boards embodying our invention, it is to be understood that various changes and modifications may be made herein without departing from the spirit of the 60 invention and the spirit and scope of the appended claims.

We claim:

1. A garment supporting attachment for ironing boards comprising a tray, means for 65 supporting the tray from an ironing board in

a position below the latter, a bracket having means by which a garment hanger is adapted to be supported therefrom, and means for supporting the bracket from the tray to occupy a position wherein portions of a garment resting upon the ironing board can be suspended from the hanger above the level of the board.

2. A garment supporting attachment for ironing boards comprising a tray, means for supporting the tray from an ironing board in a position below the latter, a bracket having its upper portion offset laterally and provided with a hook from which a garment hanger is adapted to be suspended, and means for supporting the bracket from the tray to occupy a position wherein portions of a garment resting upon the ironing board can be suspended from the hanger above the level of the board.

3. A garment supporting attachment for ironing boards comprising a tray, means for supporting the tray from an ironing board in a position below the latter, a bracket having a lower linear portion and a substantially U-shaped upper portion terminating in a hook from which a garment hanger is adapted to be suspended, a sleeve secured to the tray and slidably receiving the linear portion of the bracket for vertical adjustment of the latter, and means for securing the bracket to the sleeve in any selected position of vertical adjustment.
